MUSIC STAND.

No. 15,147.

Patented July 15, 188

UNITED STATES PATENT OFFICE.

THEODORE HERTWIG, OF NEW YORK, N. Y.

DESIGN FOR A MUSIC-STAND.

SPECIFICATION forming part of Design No. 15,147, dated July 15, 1884.

Application filed May 29, 1884. Term of patent 7 years.

To all whom it may concern:

Be it known that I, THEODORE HERTWIG, a citizen of the United States of America, residing at the city of New York, in the county 5 of New York and State of New York, have invented a certain new and original Design for Music-Stands, of which the following is a specification, reference being had therein to the accompanying drawing.

- 10 My invention relates to a design for music-stands. For the details of the invention reference is made to the accompanying illustration, wherein all the features are clearly portrayed.
- 15 The main features of the design are in the shape and ornamentation of the back or head piece A and the ornamentation of the door B, as shown. The panel of back A is provided with a triangular-shaped ornamentation, a, at each corner. The top rail of the 20 back is provided with suitable ornamental mountings, c, as shown, while upon each top

side edge of said back a knob, d, is provided. Below ornamentation c there is a representation of a spray, e, hanging from pins f. Door 25 B is provided with a central panel, g, in each corner of which is an ornamental triangle, b, similar to those a, above referred to. Enclosed within these triangles are a series of circles, in the center of the inner one of which 30 is placed a lyre, i, supported upon bracket k, and encircled by a spray of leaves, l, as shown.

What I claim is—

1. The design for music-stands herein shown.
2. In a music-stand, the design for back or 35 head piece, as herein shown.
3. In a music-stand, the design for door B, as herein shown.

In testimony whereof I affix my signature in presence of two witnesses.

THEO. HERTWIG.

Witnesses:

SIMON SULTAN,
J. GIDEON.
